(57) CLAIM

The ornamental design for a handbag with cat applique, as shown and described.

DESCRIPTION

FIG. 1 is a perspective view of the handbag with cat applique showing my new design;

FIG. 2 is a front elevation view thereof;

FIG. 3 is a left side elevation view thereof;

FIG. 4 is a top plan view thereof;

FIG. 5 is a right side elevation view thereof;

FIG. 6 is a rear elevation view thereof;

FIG. 7 is a bottom plan view thereof; and,

FIG. 8 is an exploded perspective view thereof.

The broken lines shown in the drawings of FIG. 8 illustrate portions of the handbag with cat applique that form no part of the claimed design.
